CHARLES EWEN CAMERON, JR., OF EAST ORANGE, NEW JERSEY, ASSIGNOR TO LAUTER-
HUMANA CO., A CORPORATION OF NEW JERSEY

PIANO ACTION

Application filed December 23, 1929. Serial No. 415,915.

This invention relates in general to a novel and improved piano action, and particularly to a piano action for so-called grand pianos as distinguished from upright pianos.

One object of the invention is to provide a piano action embodying novel and improved features of construction in the mechanism for striking the piano strings by the actuation of the associated "keys", whereby great sensitivity of the mechanism and rapid movement thereof may be obtained with ease of operation and resultant clearness and sharpness of tone.

The term "key" is intended to designate either the manually actuated key commonly used in hand played instruments, or to designate any other parts for imparting movements to the hammers, such as the pneumatics used in player pianos.

Another object is to provide in a piano action of this character novel and improved means for preventing or restraining rebound of the hammer after it has once struck the string to ensure that the hammer shall strike the string only once upon each actuation of the key.

Other objects are to provide a piano action which shall be simple and inexpensive in construction, and light in action or requiring a small amount of power to actuate the hammer into the contact with the string; to provide a novel and improved construction, combination and mounting of a key, hammer and means for connecting them whereby the hammer is certain to properly strike the string upon both light and heavy touch of the player upon the key, and the hammer is prevented from repeated rebounding against the string under all conditions; to provide such a novel and improved construction and combination of parts whereby the movement or momentum of the key upon the string-striking operation serves to compensate or offset recoil of the hammer from the string to prevent rebound of the hammer against the string; to provide in piano action of the character novel and improved cushioning means for absorbing the power or energy in the recoiling hammer to restrain the tendency of the hammer to rebound to the string after

the recoil, and to obtain other advantages and results as will be brought out by the following description.

Referring to the accompanying drawings in which corresponding and like parts are designated by the same reference characters throughout the several views:

Figure 1 is a side elevation of a piano action embodying my invention, showing it mounted in a frame which is shown partially in section.

Figure 2 is a top plan view of one piano action taken on the line 2—2 of Figure 1, and

Figure 3 is an enlarged fragmentary vertical sectional view through the frictional connection of the hammer lifter or jack with the key.

Specifically describing the illustrated embodiment of the invention, the reference character A designates a key frame of known construction having the usual balance rail B upon which are fulcrumed intermediate their ends, the keys C. As shown, each key preferably has a transverse tapered slot 1 which loosely receives a pivot pin 2 secured in the balance rail B, and beneath the outer end of each key is arranged a cushion stop 3 to limit swinging movement of the key in its hammer actuating movement. Beneath the other end of the key is arranged another cushion stop 4 to limit swinging of the key on its return from its hammer actuating movement. The usual key leads 5 are provided to insure the proper weight and balance of the keys.

At the inner end of each of the keys is provided a shock absorber which may consist of a cylindrical socket or recess 6 lined with a shock absorbing substance, for example, resilient rubber 7 which may be in the form of a short tube. Preferably this shock absorber also has friction producing characteristics. Within this recess is arranged the tapered or conical end 8 of a hammer lifter or jack 9, formed of wood or any other suitable material and which preferably will establish a frictional contact with the friction tube 7. At this point, it should be understood that the shock absorbing material may be placed on the end of the jack 9 instead of in the socket 6, the socket might be tapered

instead of the end of the jack, or both the walls of the socket and the end of the jack might be tapered, and the socket might be formed in the lifter and a tapered projection on the key, all within the scope of the invention. The jack 9 includes a rod 10 which has a screw-threaded and adjustable connection with the body 11 for varying the length of the lifter or jack, and a jam nut 12 preferably formed of frictional material, such as leather, is threaded on the rod to hold the parts 10 and 11 in adjusted position. The upper end of the rod 10 is hooked at 13 and passes through an opening 14 in the shank 15 of a hammer 16, and preferably the opening 14 is lined with a soft filler 17, for example, a felt bushing.

A hammer head 18 is mounted at one end of the shank 15 and the other end of the shank 20 is pivoted at 19 in a block 20 secured, as by screws 21, to a hammer supporting rail 22 so that the hammer may oscillate in a vertical plane toward and from a string D. The relative sizes of the parts and their interconnections are such that upon full movement of the key pivotally upon the pin 2 through its hammer actuating operation, the hammer is moved to a point slightly spaced from the string, as shown by dot and dash lines E. It will be noted that the distance between the points of contact of the hammer lifter or jack 9 with the key and the hammer, is less than that required to cause the hammer to contact with the string D at the end of the normal string-striking movement of the key, so that the hammer could not strike the string without the relative movement between the jack 9 and the key which is permitted by the tapered end 8 of the jack in the recess 6. However, the power and momentum caused by the actuation of the key is imparted to the hammer so that when the key strikes the stop 3, the lifter 9 may move relatively to the key so that the hammer is thrown against the string under influence of this power and momentum. This appears to be particularly effective for playing with light touch upon the key. The hammer recoils from the string as the key returns to the stop 4 upon release of pressure by the player, and the shock of the recoil is absorbed by the rubber 7 which does not have sufficient reaction on the lifter to cause the key to rebound against the string. Also the frictional contact between the rubber and the tapered end 8 of the lifter appears to in part restrain rebound of the hammer, so that the hammer is prevented or restrained from repeated striking of the string upon a single actuation of the key. When greater pressure is applied to the key by the player and the key strikes the stop 3, the other end of the key apparently rises upon the pin 2 so that the momentum and power therein in part compensate or offset the energy in the hammer upon its recoil from the string, which

in connection with the shock absorber or cushion 7 effectually prevents rebound of the hammer against the string. Therefore, it will be observed, that the combination and connection and the sensitiveness of the parts are such that the hammer can be caused to strike the string repeatedly as often and as rapidly as desired by the player, under either light or heavy touch upon the key, but regardless of the rapidity or force in the action of the keys, the hammer can strike the string only once for each actuation of the key. Clear tones are thus insured.

A damper construction is combined with the key action so as to normally damp the strings, and undamp them or move the damper from contact therewith as the hammer is actuated into contact with the string. This damper construction includes a damper crank or lever 23 pivoted at 24 on a rail 25, and with its free end overlying the inner end of the key C. A damper lifter 26 is pivotally connected at one end to the crank 23 intermediate the ends of the latter, and has attached to its upper end a damper head 27. When the key C is in normal position at rest, the damper crank 23 is forced downwardly by gravity and slightly clears the end of the key so that the damper head may rest by gravity upon the corresponding string. When the key is actuated to throw the hammer against the string, the damper crank is raised and correspondingly raises the damper head from the string just prior to the striking of the string by the hammer. When the hammer rebounds from the string, upon release of the key, the damper immediately falls by gravity upon the string so as to damp vibration thereof.

It will be observed that the piano action embodying my invention is extremely simple, embodying a small number of simple parts and a minimum number of connections between the parts. The action is thus light in weight and requires a small amount of power for operation. At the same time it is extremely sensitive and permits rapid successive striking of the strings by the hammers, as in executing a tremolo, with the important advantage of the invention that the hammer is prevented from repeated rebounding upon the string, and by extremely simple means which is incomparable with the usual mechanism for this purpose utilized in piano actions. This same means, the resilient tube 7 and the tapered end 8 of the lifter, also serve as a stop to limit recoil of the hammer from the string, thereby obviating the necessity for a stop rail for the hammers.

While I have shown and described one specific embodiment of my invention, it should be understood that this is primarily for the purpose of illustrating the principles of the invention, and that the invention may be embodied in many different details of

construction without departing from the spirit or scope of the invention.

Having thus described my invention, what I claim is:

- 5 1. In a piano, the combination with a string, of a hammer, a key, a single hammer lifter between said key and said hammer connected for relative movement with one thereof, the distance between the points of
 10 engagement of said lifter with said hammer and said key being less than that required to cause the hammer to contact with said string at the end of the string-striking movement of said key without said relative movement
 15 so that upon the string-striking movement of said key movement of said lifter will allow said hammer to be thrown against said string by the energy imparted thereto by actuation of said key and permit said hammer to recoil idly independent of said key, and shock-absorbing means both to limit recoil of the hammer and to restrain rebound of the hammer to the string.
2. In a piano, the combination with a string, of a key, a hammer, a single lifter connected at one end to said hammer, and a shock-absorbing connection between the other end of said lifter and said key to absorb the shock of the recoil of the hammer from
 30 said string.
3. In a piano, the combination with a string, of a hammer, a key, a lifter interposed between said key and said hammer for actuating the latter to strike said string, said lifter being connected to said key for relative movement and connected to said hammer to move therewith, the distance between the points of engagement of said lifter with said hammer and said key being less than that
 35 required to cause the hammer to contact with said string at the end of the string-striking movement of said key without said relative movement, so that upon string-striking movement of said hammer said lifter will move relatively to said key and said hammer will be thrown against said string by the energy imparted to it by actuation of said key and said hammer will recoil idly independent of said key, and shock-absorbing
 40 means to limit recoil of the hammer and restrain rebound of the hammer to the string.
4. In a piano, the combination with a string, of a hammer, a key having a recess, and a lifter interposed between said key and said hammer for actuating the latter to strike said string, said lifter having a portion to fit into and to contact with and move relatively to the walls of said recess and being connected to said hammer to move therewith, said walls of said recess having shock-absorbing qualities, the distance between the points of engagement of said lifter with said hammer and the walls of said recess being less than that required to permit said hammer to contact with the string at the end of
 45 the string-striking movement of said key without such relative movement between said key and said lifter, so that upon swinging of said key in one direction said lifter will move relatively to said key to cause the hammer to be actuated to strike said string under the energy imparted to it by said actuation of the key, and a shock-absorber against which said hammer can recoil to restrain rebound of the hammer.
5. In a piano, the combination with a string, of a hammer, a key having a cylindrical recess provided on its walls with shock-absorbing and friction-producing material, and a lifter interposed between said key and said hammer for actuating the latter to strike said string, said lifter having a tapered portion to fit into and frictionally engage the walls of said recess to move relatively thereto and being connected to said hammer to move therewith, the distance between the points of engagement of said lifter with said hammer and the walls of said recess being less than that required to permit said hammer to contact with the string at the end of the string-striking movement of said key without said relative movement between said lifter and the walls of said recess, so that upon string-striking movement of said hammer said lifter will move relatively to said key to cause said hammer to be thrown against said string by the energy imparted to it by actuation of said key, and said shock-absorbing material upon recoil of said hammer from the strings will prevent rebound of the hammer to the string.
6. In a piano, the combination with a string, of a hammer pivotally mounted at one end, a key pivotally mounted intermediate its ends, stops at each end to limit pivotal movement, said pivotal mounting being such as to permit bodily movement of the key on said mounting toward said string when pivotal movement is stopped, a lifter pivotally connected at one end to said hammer and connected to one end of said key for movement relative thereto, the distance between the points of engagement of said lifter with said key and said hammer being less than required to permit said key to contact with the string at the end of the string-striking movement of said key without such relative movement between said key and said lifter, so that upon swinging of said key in one direction said lifter will move relatively to said key to cause the hammer to be actuated to strike said string under the energy imparted to it by said actuation of the key, and a shock-absorber against which said hammer can recoil to restrain rebound of the hammer.
7. In a piano, the combination with a string, of a hammer pivotally mounted at one end, a key pivotally mounted intermediate its ends, stops at each end of said key to limit pivotal movement, said pivotal mounting be-

ing such as to permit bodily movement of the key on said mounting toward said string when pivotal movement is stopped, and a lifter pivotally connected at one end to said hammer, 5 means connecting the other end of said lifter to one end of said key for relative movement including a shock-absorber, the distance between the points of engagement of said lifter with said key and said hammer being less than 10 required to permit said key to contact with the string at the end of the string-striking movement of said key without said relative movement between said key and said lifter, so that upon swinging of said key in one direction 15 said lifter will move relatively to said key to cause said hammer to be actuated to strike said string under the energy imparted to it by actuation of said key, and the shock of the recoil of said hammer will be absorbed 20 by said shock-absorber to restrain rebound of the hammer.

8. In a piano, the combination with a string, of a hammer pivotally mounted at one end, a key pivotally mounted intermediate 25 its ends, stops at each end of the key to limit pivotal movement, said pivotal mounting being such as to permit bodily movement of the key on said mounting toward said string when pivotal movement is stopped, one end of said 30 key having a recess provided with shock-absorbing walls, a lifter connected at one end to said hammer and having its other end tapered and fitted into said recess to move into and out thereof, the distance between the points 35 of engagement of said lifter with said key and said hammer being less than required to permit said key to contact with the string at the end of the string-striking movement of said key without relative movement between 40 said key and said lifter, so that upon swinging of said key in one direction said lifter will move relatively to said key to cause said hammer to be actuated to strike said string, and the shock of the recoil of the hammer will 45 be absorbed by said walls of said recess.

9. The piano set forth in claim 8, wherein said tapered end of the lifter has a releasable frictional engagement with said walls of the recess.
